ELECTRODE HOLDER

Carl Mathews and Charles Chinzi,
Jackson, Mich.

Application September 2, 1943, Serial No. 500,966

1 Claim. (Cl. 219—8)

This invention relates to an electrode holder, and has for the primary object the provision of a device of this character which will be extremely convenient to handle and permit welding operations and the like to be easily and quickly carried out and is of a construction that will assure against the accidental displacement of the electrode and still permit its application and removal to be quickly carried out when desired.

Another object of this invention is the provision of means for cooling the holder and to reduce to a minimum the amount of heat which may be transmitted thereto throughout its length so that the device may be more comfortable to use and less apt to subject the operator to burns.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawings, in which

Figure 1 is a side elevation illustrating an electrode holder constructed in accordance with our invention.

Figure 2 is a top plan view illustrating the device.

Figure 3 is a transverse sectional view taken on the line 3—3 of Figure 1.

Figure 4 is a sectional view taken on the line 4—4 of Figure 2.

Figure 5 is a sectional view taken on the line 5—5 of Figure 1.

Figure 6 is a sectional view taken on the line 6—6 of Figure 4.

Figure 7 is a transverse sectional view taken on the line 7—7 of Figure 4.

Figure 8 is a transverse sectional view taken on the line 8—8 of Figure 5.

Referring in detail to the drawings, the numeral 5 indicates an elongated tubular grip or handle, constructed of a material which will be non-conductive of heat as well as electricity. An outer sleeve 6 extends into the bore of the handle or grip 5 and is removably secured therein by set screws 7 countersunk in the handle or grip. The outer sleeve 6 is of conductive metallic material and has one end remotely located to the handle or grip and enlarged and apertured, as shown at 7', to freely receive an electrode 8. The other end of the outer sleeve terminates flush with the butt or rear end of the handle or grip 5 and frictionally receives therein a conduc-

tive socket type fitting 9 in which may be secured the terminal end of an electric lead. The securing of the terminal end of the lead in the fitting 9 can be carried out in any well known manner and the inner end thereof forms an abutment for one end of a coil spring 10.

Mounted for sliding movement in the outer sleeve 6 is an inner sleeve 11 carrying at one end a forked head 12 adapted to engage and force the electrode tightly against the walls of the opening 7' to prevent accidental displacement of the electrode. The other end of the inner sleeve 11 is acted upon by the spring 10 to urge the head 12 into a position of tightly wedging the electrode against displacement. It is preferable that blocks 13 be arranged between the inner ends of the inner sleeve 11 and one end of the coil spring 10 and between the fitting 9 and the other end of the coil spring.

A trigger 14 is slidably mounted on the handle or grip 5 and has detachably secured thereto a pin 15 detachably secured to the inner sleeve and operating in a slot 16 provided in the outer sleeve 6. A sliding movement of the trigger 14 in one direction correspondingly moves the inner sleeve 11 disengaging the head 7 from the electrode permitting the latter to become free for removal. With the head 12 in a retracted position, the electrode can be adjusted or another substituted therefor. The head 12 may be secured on the inner sleeve in any well known manner. As soon as the trigger 14 is manually released the spring 10 acts to engage the head 12 with the electrode.

The forward end of the handle or grip 5 is equipped with a removable guard plate 17 acting to shield the hand of the operator.

A cooling jacket 17' is mounted on the outer sleeve 6 and surrounds the opening 7' thereof. The cooling jacket 17' mounted on the outer sleeve forms a fluid space 18 which extends about the opening 7' for the purpose of permitting a cooling fluid to be circulated about the opening 7' and in close proximity to the electrode for the purpose of carrying off heat.

Inlet and outlet pipes 19 and 20 are connected to an end wall of the cooling jacket and parallel the outer sleeve 6 and extend through openings provided in the handle or grip 5. The free ends of the pipes 19 and 20 are provided with fittings 21 to which flexible conduits leading from a source of fluid supply may be connected. The fluid enters the jacket by way of the pipe 19 and escapes by way of the pipe 20. The pipe 19 is of a greater length than the pipe 20 and ter-

minates adjacent the opening 7' so that the cooling fluid will be delivered into the jacket close to the opening 7'. The pipes 19 and 20 may be sectional and connected by couplings 22 for the purpose of rendering the assembling of the device more convenient.

While we have shown and described the preferred embodiment of our invention, it will be understood that minor changes in construction, combination and arrangement of parts may be made without departing from the spirit and scope of the invention, as claimed.

Having thus described the invention, what we claim is:

In an electrode holder, an outer sleeve having openings arranged oppositely to each other and adjacent one end of said sleeve to receive an electrode, said end of the sleeve being enlarged and provided with a curved wall to engage the electrode between said openings, a handle secured to the sleeve, a spring pressed inner sleeve slidable in the outer sleeve and including a solid forked

head at one end operating in the enlarged end of the outer sleeve to engage and force the electrode against the curved wall of the enlarged end of the outer sleeve between said openings, manually operated means carried by the handle and connected to the inner sleeve for retracting the head from the electrode, a cooling jacket mounted on and surrounding a portion of the outer sleeve and the enlarged end thereof, said jacket having opposite walls flattened against the enlarged end of the outer sleeve and provided with openings matching the first-named openings to permit the electrode to extend therethrough, and inlet and outlet cooling fluid conduits connected to the jacket with the discharge end of the inlet conduit located adjacent the enlarged end of the outer sleeve and the flattened walls of the jacket to cause cooling fluid to pass in contact with the curved wall of the enlarged end of said outer sleeve.
